UNITED STATES PATENT OFFICE.

JOHN T. SALTIEL, OF LOS ANGELES, CALIFORNIA.

CONCRETE BUILDING CONSTRUCTION.

1,070,921.

Specification of Letters Patent. Patented Aug. 19, 1913.

Application filed July 16, 1912. Serial No. 709,782.

To all whom it may concern:

Be it known that I, JOHN T. SALTIEL, a citizen of the United States of America, residing at Los Angeles, in the county of 5 Los Angeles and State of California, have invented new and useful Improvements in Concrete Building Construction, of which the following is a specification.

This invention relates to improvements in 10 concrete building construction and has particular application to reinforced concrete structures. It is to be understood, however, that the invention in its useful application is not limited to concrete construction, 15 as the same may be employed wherever reinforced plastic materials are utilized for building and other purposes.

In carrying out the present invention, it 20 is my purpose to provide means whereby the reinforcing means of the plastic mass may be held within such mass and away from the forms or false work, so that the reinforcing means may be embedded in the plastic mass in an even and uniform manner so as to strengthen the structure. 25 Furthermore, I aim to provide means for holding or supporting the reinforcing means for the plastic material away from the forms so that the plastic mass forming the 30 structure may surround the reinforcing elements whereby such mass will possess relatively great strength after the same has settled, the means preferably embracing the constituent parts of the plastic mass and 35 remaining therein after such mass has settled and become hardened.

With the above and other objects in view, the invention consists in the construction, 40 combination and arrangement of parts hereinafter set forth in and falling within the scope of the claim.

In the accompanying drawings there has 45 been illustrated certain preferred and practical embodiments of my invention, and in these drawings, Figure 1 is a detail perspective view of a plurality of intersecting reinforcing bars equipped with the present invention. Fig. 2 is an enlarged perspective view of a detail of Fig. 1. Fig. 50 3 is a sectional view of a reinforced plastic mass illustrating the application of the present invention, the plastic material being mounted upon the form. Fig. 4 is an enlarged transverse sectional view of one of 55 the supports of the reinforcing bar shown in Fig. 1, the parts being broken away. Fig.

5 is a top plan view of a modified form of the invention. Fig. 6 is a perspective view of a further modification of the invention, and Fig. 7 is a sectional view through the 60 support shown in Fig. 6.

In the building of reinforced concrete structures and the like, the reinforcements are usually placed upon forms or false work commonly known as framing and the concrete or other plastic material poured upon the form and around the reinforcing means. Heretofore, it has been a common practice for the workmen employed to utilize anything handy for the purpose of spacing the 70 reinforcing bars and the like from the forms, so that the plastic mass would incase the reinforcements. This method of maintaining the reinforcements spaced from the forms has many objectionable features 75 among which may be enumerated, the lack of uniformity resulting from uneven positioning of the reinforcements throughout the body of the plastic mass, incident to the utilization of wooden and iron plugs, 80 strips and the like of various lengths to hold the reinforcements spaced from the framework, and the weakening of the hardened mass resulting from the uneven positions of the reinforcements. By means 85 of my invention, these and other objectionable features heretofore inherent in reinforced concrete building construction are eliminated, and the reinforcements spaced from the forms in an even and uniform 90 manner so that the plastic mass or material may incase the forms, and when hardened, possess the strength commensurate with the bulk of the plastic mass and the reinforcing means therein. The supports for holding the reinforcing means spaced from the forms preferably embrace the constituent 95 parts of the plastic mass and are embedded therein so that when the mass has settled or hardened, an integral structure will be 100 presented and the reinforcements arranged therein in an even and uniform manner to equalize and distribute the weight to all parts of the structure.

Referring now to the accompanying drawings in detail, and particularly to Figs. 1 to 4 inclusive. A designates the form or false work commonly known to those skilled in the art as framing, and upon such forms or false work are arranged my improved 110 means for holding the reinforcements spaced from the form. This holding means, in the

present instance, embraces a plurality of blocks *a* each having formed in one surface a longitudinal relatively deep groove 1 and a shallow groove 2 arranged at right angles 5 to the groove 1 and intersecting such groove approximately centrally of the block. This form of my invention is designed to be utilized in conjunction with reinforcing bars of any cross sectional contour which bars, 9 are, as usual arranged longitudinally and transversely of the plastic mass, the longitudinal bars being indicated at 3 while the transverse bars are denoted by the numeral 4. The longitudinal bars herein shown are 15 arranged beneath the transverse bars and are disposed in the relatively deep groove 1, while the transverse bars lie within the shallow groove 2 and above the bars 3. If desired, the various bars, at the points of 20 intersection, may be tied to each other by means of wire or the like 5 to maintain the bars in proper position. After the holding blocks and bars have been positioned upon the framing, the concrete or other plastic 25 material is poured upon the same and owing to the reinforcing bars being spaced from the frame, such bars will be incased in the mass and the blocks embedded therein.

The manner of assembling the blocks just 30 described may be briefly stated as follows: Assuming the framing or form to be assembled, the blocks *a* are positioned thereupon and arranged at appropriate distances apart. The longitudinal reinforcing bars are 35 then placed upon the blocks and in the alining relatively deep grooves thereof, subsequent to which action the transverse bars 4 are placed in the alining shallow grooves of the respective blocks and upon the longitudinal bars. The tie wires, if such are used, may then be wrapped about the respective bars at the points of intersection. The concrete C or other plastic material is now poured over the reinforcing bars and 45 blocks and envelops the reinforcing bars, incident to the same being spaced from the form, and when the mass becomes set or hardened, the blocks *a* will be embedded therein and form therewith an integral 50 structure.

The form of block disclosed in the modification illustrated in Fig. 5 is designed for use with wire screening or the like for reinforcing the plastic mass, and this block is 55 provided with a plurality of spaced right angularly disposed grooves 14 to accommodate the segregated wires of the screen, as will be readily understood.

Referring now to the block disclosed in 60 the modification illustrated in Fig. 6 the bottom of the block is provided with right angularly disposed intersecting grooves 14

and 15 intersecting each other approximately centrally of the block and merging into grooves 16 at the sides of the block 65 and at the opposite extremities of each of the intersecting grooves, the grooves 16 at the sides of the block contiguous the groove 14, merging into the relatively deep groove 1 in the upper surface of the block while the 70 grooves 16 contiguous the groove 15 merge into the shallow groove 2 in the upper surface of the block. The purpose of this construction is to enable the blocks to be fastened to the intersecting reinforcing bars, tie 75 wires or the like being wrapped around the intersecting portions of the reinforcing rods and disposed within the grooves at the sides and bottom of the spacing or holding blocks. In the construction of the blocks 80 just described, it will be noted that the tie wires for fastening the reinforcing rods to one another and to the blocks are held spaced from the form or framing and owing to the grooves in the bottom and sides of 85 the blocks, the plastic mass is permitted to enter the grooves and solidify therein with the effect to cover the wires, thereby rendering the wires invisible when the plastic mass has settled and hardened. 90

From the foregoing description taken in connection with the accompanying drawings, the construction and manner of employing my invention will be readily understood by those skilled in the art, and while I have herein shown and described certain forms of my invention by way of illustration, it is to be understood that I do not confine myself to any particular arrangement of the grooves within the blocks, or to 100 the precise details of construction herein described and delineated, as modification and variation may be made within the scope of the claim and without departing from the spirit of the invention. 105

I claim:

As an article of manufacture, a block for holding the reinforcing bars of a plastic mass spaced apart from the form or false work, said block having intersecting grooves 110 formed in both the upper and lower faces thereof and grooves in the sides thereof interconnecting the first-named grooves, certain of the grooves being designed to receive the bars at points of intersection of 115 the latter, and tie wires binding the bars at the points of intersection and wrapped about said block in the side grooves therein.

In testimony whereof I affix my signature in presence of two witnesses.

JOHN T. SALTIEL.
